UNITED STATES PATENT OFFICE

2,440,881

PROTECTOR FOR PERMANENT WAVING
MACHINES

Edward Arthur Tefft, Bell, Calif.

Application February 5, 1947, Serial No. 726,536

6 Claims. (Cl. 132—34)

1

My invention relates to devices used in the art of hair curling and particularly to devices for holding locks of hair in tightly curled condition while subjecting them to heat in order to give the hair a "permanent wave."

In giving hair a permanent wave treatment it is necessary to clamp each lock of hair to be curled in a small device acting to hold the hair in a tight curl, the device being then placed, holding the tightly curled lock, in a heating unit of a heating machine for a sufficient length of time to set the curl, after which time the heating unit is removed and the lock of hair released from the device. Curling of the hair is generally required from as close as possible to the root of the hair to the tip, and the hair should be stretched while in curling position.

In order to hold the lock of hair so that the treatment causes no discomfort either from the heat of the heating unit or from the hair being pulled from the scalp, devices of the kind to which the invention relates comprise a small clamp to hold each lock of hair to be treated and a spool or mandrel mounted on the clamp, on which the lock of hair may be tightly wound and securely retained in wound condition during the heating operation.

The clamps should be readily releasable when the heating is completed, without pulling the hair and causing discomfort to the customer. Various devices of the kind referred to have been proposed or are in use, but to the best of my knowledge possess disadvantages such as undue complication or the provision of several separable parts and the like.

It is an object of my invention to provide a novel device for use in permanent wave treatment comprising only a simple clamping device carrying a one way winding means for a spindle forming a part of the device.

It is another object of my invention to provide a novel device of the kind described adapted to use either wooden or metallic spindles of simple form, and which are inexpensive to manufacture, since the spindle is not furnished with any cooperating parts requiring accurate machining.

It is a further object of my invention to provide a novel device of the kind described in which a spindle, on which the hair is wound, is carried by a clamp holding a lock of hair, by a mounting and operating arrangement permitting the spindle to be released from the clamp with a minimum of movement of the spindle relative to the body of the clamp.

2

A still further object of my invention is to provide a novel device of the kind described in which a simple clamp is provided with a single clamping and winding element permanently attached to the clamp and co-operating with a one piece spindle.

A further object of my invention is to provide a novel clamping means for use in positioning and releasing a protecting and outer clamp of a permanent wave system adjacent the scalp, and on which outer clamp tufts of hair are rolled or wound, and which clamping means, are capable of being quickly and easily secured in position and disengaged from operational position, and also in connection with which either a metal, but preferably a wooden mandrel may be used.

Other objects, advantages and features of invention may appear from the accompanying drawing, the subjoined detail description and the appended claims.

The accompanying drawing illustrates the invention in a form I at present deem preferable.

Figure 1 is a plan view of the device of my invention in open position and with the mandrel removed for purposes of clearness.

Fig. 2 is a side elevation of the device with a spindle or mandrel shown in position therein.

Fig. 3 is an end elevation of the device on enlarged scale and with a wooden spindle mounted therein, the device being shown in closed position.

Fig. 4 is a plan view of the device on substantially the same scale as Fig. 3 and with the clamping members in closed position, but with the locking member which serves both as a rotary bearing and clamp operating means in position to be moved to either locking position or to open position.

Fig. 5 is a fragmentary detail, on still larger scale and partly in section, and as viewed on line 5—5, Fig. 3 showing a clamping member in operative position.

Fig. 6 is a detail partly in section on further enlarged scale, as viewed on line 6—6, Fig. 2.

Fig. 7 is a section of the ratchet and locking means, taken on line 7—7, Fig. 6.

In Fig. 1 the numeral 10 indicates one clamping bar pivoted at 12 to the offset end 14 of a second clamping bar 16. The clamping members or bars 10 and 16 may be made of strip metal and are covered with rubber sheathing 18 serving both to give a secure grip of the members on a lock of hair and to insulate from the scalp of the person undergoing treatment the bars, which many times get quite hot.

A portion of offset 14 is bent up to form a bearing 20 in and against which a cylindrical end 21 of a mandrel or spindle 22 is mounted when a lock or tuft of hair has been wound around the spindle 22 and the lock of hair is clamped between bars 10 and 16.

The clamping members 10 and 16 are adapted to be brought into engagement with one another by means of a double armed link 24 pivoted at 26 to the free end of clamping member 16. At the free end of the link 24 and between the arms of the link on a stem 30 passing through both arms of the link 24, a cam 28 is mounted and which cam is rigidly secured on the stem in any suitable manner as for instance by soldering or brazing it thereto. A bushing 32 is fitted on and secured to one end of the stem, and a spring washer 36' is arranged between a head 34 on the oppositely projecting end of the stem and the adjacent arm of link 24, thus bushing 32 is drawn toward the opposite arm of the link.

A combined operating member and rotary bearing assembly 36 is formed by a strip of sheet metal bent to embrace the bushing 32 and is pinned thereto as indicated at 38. The ends of the strips are formed into a bearing 39 for a circular disc 40 and support it for rotary motion. The disc 40 is provided with a laterally extending finger piece 42 by which the bearing may be turned about the axis of the bushing 32, and the link 24 may be swung about pivot 26. The edge of disc 40 is provided with serrations 44 and a spring detent 46 positioned between the lower end of sleeve 32 and link 24 is arranged with its end 48 projecting into the rotary bearing to engage the serrated edge of disc 40 to permit rotating of said disc 40 in one direction only.

It will be noted that the arrangement described will permit disc 40 to be turned in a direction such that the serrations ride under the end 48 of spring detent 46 but cannot be turned in the opposite direction since the serrations will engage against the end 48 of the detent.

A square aperture 50 is cut in the disc 40 and the finger piece 42 is recessed at 52 to enable the squared end 56 of the spindle 22 to be inserted into the square hole in the disc 40 and recess in the finger piece.

Spindle 22 is preferably made of wood since this material is a poor conductor of heat, but as it is sometimes desirable to supply extra heat at certain points of a head of hair or under certain conditions a metal spindle may also be used.

In using the device of my invention, a lock or tuft of hair is separated from the remainder of a person's head of hair and clamped between the clamping members 10 and 16 by closing the bars on the lock of hair and swinging link 24 toward and onto the end of bar 10 with the operating member 36 extending forwardly beyond the link, in which position the low portion of cam 28 can pass over the projecting end 29 of bar 10. The operating member is then swung toward the link with the finger piece 42 away from the clamp thus bringing the high point of the cam against end 29 and clamping bars 10 and 16 together. The lock of hair may then be moistened with any desired preparation and wound upon the spindle 22.

When the tuft of hair is wound around the spindle so that the spindle approaches the clamp, the cylindrical end 21 of mandrel 22 is placed against the fixed abutment 20, and the squared end 56 is inserted in the square hole in the ro-

5 tary bearing 36 and the hair is further tightened around the mandrel 22 by turning finger piece 42 to wind the hair tightly therearound. The hair may then be moistened or treated as required, wrapped in a protective cover and placed in a heating unit of any suitable heating machine. The described procedure is carried out with all portions of the hair required to be treated.

When heat has been applied for the required 10 length of time the devices are removed from the heating units, and by swinging the rotary bearing assembly away from the spindle 22, the spindle may be easily and quickly removed from the clamp and from the curled hair, the clamping members 10 and 16 are then released by swinging the assembly 36 to the position shown 15 in Fig. 4 so as to remove the cam pressure holding the clamp bars 10 and 16 together and then by swinging the link on which the rotary bearing 20 is mounted clear of the end 29 of clamping member 10 as shown in Fig. 1.

I claim:

1. In a device for permanent hair waving including: a hair lock clamping member; another 25 hair lock clamping member co-operating with the first lock clamping member and hinged at one end to one end of said first lock member; a fixed bearing for a spindle mounted at one end of said members, a rotary bearing mounted at the 30 opposite end of said members for swinging movement into and out of operative position; means for rotating said bearing in one direction; means for preventing rotation of said bearing in a direction opposite to that in which it is rotated by 35 said means for rotating it; and readily releasable means for clamping together said clamping members.

2. A device as set forth in claim 1 and in addition comprising a spindle having one end cylindrical in shape to rotate against said fixed bearing and its opposite end shaped to engage in and be rotated by said rotary bearing.

3. In a device for permanent wave treatment 45 of hair, including: a hair lock clamping member; another hair lock clamping member hingedly connected at one end to one end of said first mentioned member; a swinging link hinged to the other end of one of said clamping members; a fixed bearing for a spindle mounted at the 50 hinged end of said clamping members; a rotatable bearing mounted on said swinging link; means for rotating said bearing in one direction; means for preventing rotation of said bearing in a reverse direction; and a spindle supported by said fixed bearing and rotatable bearing.

4. In a device for permanent wave treatment 60 of hair, including: a pair of hair lock clamping members hingedly connected at one end; a swinging link pivoted to the other end of one of said clamping members; a stem projecting from said swinging link; a cam mounted on said stem in a position to be brought against the free end of the other of said clamping members; a rotary bearing secured to said stem; and means for rotating said rotary bearing.

5. A hair curling device, including: a first hair 70 lock clamping member having a camming surface, a second lock clamping member hingedly connected at one end to one end of said first clamping member; a bearing carried at the hinged end of said clamping members; a swinging link pivoted at one end to the free end of said second clamping member; a stem mounted at the free 75 end of said link; a rotary bearing member

mounted on and secured to said stem and adapted to be brought into axial alignment with said first mentioned bearing and having an opening therein; a cam mounted on said stem and adapted to be brought into camming engagement with said camming surface by the movement of said rotary bearing member into said axial alignment with said first mentioned bearing; means carried on said swinging link to permit rotation of said rotary bearing in one direction and to prevent rotation of said bearing in an opposite direction; and a spindle one end of which is cylindrical and the other end of which is adapted

to be inserted into said opening and being so shaped as to be rotated by said rotary bearing.

6. A hair curling device as set forth in claim 5 and in which said rotary bearing comprises a toothed disc, a mount holding said disc for rotation in a plane transverse to the axis of said spindle, a finger piece projecting from said disc whereby said disc may be rotated, and a detent engaging with said toothed disc to permit rotation thereof in one direction and to prevent rotation thereof in the opposite direction.

EDWARD ARTHUR TEFFT.
